UNITED STATES PATENT OFFICE.

ROBERT W. SCOTT, OF PHILADELPHIA, PENNSYLVANIA, ASSIGNOR OF ONE-HALF TO LOUIS N. D. WILLIAMS, OF ASHBOURNE, PENNSYLVANIA.

KNITTED FABRIC.

SPECIFICATION forming part of Letters Patent No. 709,827, dated September 23, 1902.

Application filed February 25, 1902, Serial No. 95,505. (No specimens.)

To all whom it may concern:

Be it known that I, ROBERT W. SCOTT, a citizen of the United States, residing in Philadelphia, Pennsylvania, have invented certain 5 Improvements in Knitted Fabrics, of which the following is a specification.

My invention consists of a fabric comprising two webs practically independent of each other, but held or tied at intervals by yarns 10 different from those which constitute the webs, the two webs lying closely together, so as to provide a double web joined at the desired points.

The two views in the accompanying drawings 15 illustrate different methods of securing together the two webs in accordance with my invention.

The fabric consists of two single webs, each preferably tubular and one overlying the 20 other, as shown at 1 and 2, these webs being held or tied together at the desired points. For the purpose of thus holding or tying together the two webs I employ yarn or yarns 25 separate from those constituting the webs and forming courses which may be parallel either with the needle-wales or the courses of said webs, the tying-yarns overlying wales of one web and forming loops or stitches in wales of the other web, or, if desired, forming loops 30 or stitches in wales of both webs.

In Figure 1 of the drawings I have shown various ways of manipulating the tying-yarn so as to form courses in line with the needle-wales of the fabric. Thus the tying-yarn x has 35 loops engaging a needle-wale of the back web and overlies sinker-wales of the front web in its passage from loop to loop, a tying-yarn x' forms stitches in a wale of the back web instead of simple loops, a tying-yarn x^2 forms 40 loops in a needle-wale of the face web and overlies sinker-wales of the back web, a tying-yarn x^3 forms stitches instead of loops in a wale of the face web, a tying-yarn x^4 forms first a loop in a wale of the face web then a 45 loop in a wale of the back web and floats between the tying-points, and a tying-yarn x^5 forms first a stitch in a wale of the face web then a stitch in a wale of the back web, and floats between the tying-points.

50 In the fabric shown in Fig. 2 the tying-

yarns instead of running parallel with the needle-wales of the fabric run parallel with the courses of the latter, the yarn x^6 forming loops in the wales of the back web and overlying wales of the face web, the yarn x^7 forming 55 stitches in the wales of the back web and overlying wales of the face web, the yarn x^8 forming loops in wales of the face web and overlying wales of the back web, the yarn x^9 forming stitches instead of loops in said face 60 wales, the yarn x^{10} forming loops in wales of both back and face webs and floating between the tying-points, and the yarn x^{11} forming stitches in wales of both back and face webs and floating between the points. 65

Where the tying loops or stitches are formed in wales of both webs they need not be formed in adjoining courses, but may be separated by any desired number of intervening courses.

The independent tying-yarns may, if desired, be of a color different from that of the 70 yarn of either web or may be otherwise distinguished therefrom, so as to form stripes on the surface of the fabric, thus serving the double purpose of uniting the webs together 75 and providing a means of ornamenting the surface of the fabric.

The term "sinker-wales," as herein employed, means those portions of the knitting-yarn which extend from one needle-wale to 80 the next.

The fabric can be produced upon a machine having two needle-carriers with one or more yarn-guides for each needle-carrier, one yarn-guide or set of yarn-guides feeding yarn to 85 the needles of one needle-carrier to produce one web and the other yarn-guide or set of yarn-guides feeding yarn to the needles of the other needle-carrier for the production of the other web. 90

In addition to the knitting-yarn guides there will in producing the fabric having the tying-yarn extending in the direction of the needle-wales be independent yarn-guides—one for each tying-needle or group of needles—and 95 in producing the fabric having the tying-yarn extending in the direction of the courses of stitches a special yarn-guide for applying said yarn to the successive tying-needles or groups of needles throughout the set, the 100

needle or needles engaging the yarn when a loop of the same is to be drawn, and the yarn passing clear of the needles when it is to float.

Any one or more of the different methods 5 of tying the webs together shown in Figs. 1 or 2 may be employed, any desired number of wales or courses of the knitted web intervening between the courses of tying-yarn and any desired number of courses or wales of the 10 knitted web intervening between the tying-points of said tying-courses.

When the floating portions of the tying 15 yarn or yarns are on the back of the fabric, these floating portions may be permitted to remain; but when a reverse construction is adopted and the floating portions of the tying 20 yarn or yarns are upon the face of the fabric such floating portions may be removed if their presence is objectionable provided the tying-yarn has formed groups of loops or 25 stitches in wales of both webs, so that the presence of the floating portions of the tying yarn or yarns is not necessary to hold the webs together.

25 Instead of disposing the tying-yarns in courses parallel with the wales the same may be disposed in inclined or zigzag courses, if desired, the tying-yarn forming a loop or stitch first in one wale and then in another 30 wale. In fact the number and disposition of the tying-points can be varied as the character of the fabric or the uses for which it is intended may suggest.

Having thus described my invention, I 35 claim and desire to secure by Letters Patent—

1. A knitted fabric comprising two webs one overlying the other, said webs being held together by a knitting yarn or yarns independent of those of which the webs are composed, substantially as specified.

40 2. A knitted fabric comprising two webs one overlying the other, said webs being held

together by yarn or yarns independent of those of which the webs are composed, and 45 engaging with wales of the two webs alternately, substantially as specified.

3. A knitted fabric comprising two webs one overlying the other said webs being held together by yarn or yarns independent of 50 those composing the webs and forming loops or stitches in wales of the webs alternately, substantially as specified.

4. A knitted fabric comprising two webs one overlying the other, said webs being held 55 together by yarn or yarns independent of those composing the webs, forming loops or stitches in wales of the webs alternately, and floating from each group of loops or stitches to the next, substantially as specified.

60 5. A knitted fabric comprising two webs, one overlying the other, said webs being held together by yarn or yarns independent of those of which the webs are composed, the tying yarn or yarns extending in the direction of the courses of stitches of the knitted webs, and engaging with wales of the two webs alternately, substantially as specified.

65 6. A knitted fabric comprising two webs, one overlying the other, said webs being held 70 together by yarn or yarns independent of those composing the webs, said tying yarn or yarns extending in the direction of the courses of stitches of the knitted webs, forming loops or stitches in wales of the webs alternately, and floating from each group of loops or stitches to the next, substantially as specified.

75 In testimony whereof I have signed my name to this specification in the presence of 80 two subscribing witnesses.

ROBERT W. SCOTT.
